(57) **CLAIM**

We claim the ornamental design for a faucet, as shown and described.

DESCRIPTION

FIG. 1 is a top, front, left perspective view of an embodiment of the claimed design;

FIG. 2 is a top, front, right perspective view thereof;

FIG. 3 is a left perspective view thereof;

FIG. 4 is a front perspective view thereof;

FIG. 5 is a front elevation view thereof;

FIG. 6 is a rear elevation view thereof;

FIG. 7 is a right elevation view thereof, the left elevation view being a mirror image thereof;

FIG. 8 is a top plan view thereof;

FIG. 9 is a bottom plan view thereof;

FIG. 10 is a top, front, left perspective view of another embodiment of the claimed design;

FIG. 11 is a top, front, right perspective view thereof;

FIG. 12 is a left perspective view thereof;

FIG. 13 is a front perspective view thereof;

FIG. 14 is a front elevation view thereof;

FIG. 15 is a rear elevation view thereof;

FIG. 16 is a right elevation view thereof, the left elevation view being a mirror image thereof;

FIG. 17 is a top plan view thereof; and,

FIG. 18 is a bottom plan view thereof.

The ornamental design which is claimed is shown in solid lines in the drawings: The broken line portion(s) of the drawings are for illustrative purposes only and form no part of the claimed design. Broken line disclosure formed by equal length dashes show unclaimed portions of the design. Broken line disclosure formed by unequal length dashes show boundaries between claimed and unclaimed portions of the design. Broken line disclosure formed by jagged lines indicate portions of indeterminate length.
